UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

SHELF EXTENSION.

Application filed September 22, 1919. Serial No. 325,286.

To all whom it may concern:

Be it known that I, WALTER N. VANCE, a citizen of the United States, residing in Chicago Heights, in the county of Cook and State of Illinois, have invented a new and useful Improvement in Shelf Extensions, of which the following is a specification:

This invention relates in general to shelf and rack construction and the like and has 10 more particular reference to constructions of this character provided for variable assemblage.

The invention has for a principal object the provision of means for effectively and 15 easily permitting upward extension of such assemblages beyond the height of the uprights provided and this without requiring the use of devices which would in any fashion mar the appearance of the extended assembly or protrude out to interfere with the easy insertion of articles into the racks or shelves or other arrangement.

The invention contemplates the provision 20 of internal connectors for upright extension, which without requiring auxiliary fastening devices to secure them to either of the connected parts, will firmly and securely hold the connected parts together. In this connection the invention has the further 25 important purpose of providing connectors having such secure holding qualities which will be easily insertable into uprights already erected in the assemblage and which may be easily removed.

Another important object of the invention 30 is the provision of connectors of this character which may be cheaply and easily manufactured.

Numerous other objects and advantages 35 of the invention will be apparent as it is better understood from the following description when considered in connection with the accompanying drawing illustrating a preferred embodiment thereof.

Referring to the drawing,

Figure 1 is a perspective view of a portion 40 of shelf assemblage including connectors constructed in accordance with my present invention;

Fig. 2 is a partial enlarged side elevation showing an upright and an extension thereof;

Fig. 3 is a section taken substantially on the line 3—3 of Fig. 2;

Fig. 4 is a perspective view of a connector; 55

Fig. 5 is a section taken substantially on the line 5—5 of Fig. 6;

Fig. 6 is a side elevation thereof; and

Fig. 7 is a plan view of a blank used in 60 making said connector.

For the purpose of illustrating my invention I have shown on the drawing a partial shelf assemblage comprising uprights 11 of tubular form and rectangular in cross-section. These uprights are provided with slots 12 in which are secured front and back bearers or cross-supports 13 and front-to-back bearers or cross-supports 14. These front and back or lengthwise bearers 13 and 70 front-to-back or crosswise bearers 14 with the uprights constitute a frame for the shelves which are indicated at 16.

Into the open ends of the tops of the uprights are inserted extension connectors 17, 75 shown more in detail in Figs. 4 to 7. Considering Fig. 7 which shows a blank from which each connector is made, the dotted line identified by reference character 18 indicates a central transverse line of bend, the 80 material of the blank being notched at each side at 19 to provide cut-away edge portions as indicated at 21. Reference character 22 indicates two lines of fold, the material at 23 at each side being bent up to form lateral 85 flanges. These flanges are bent up from the plane of the blank and the blank is then bent in the opposite direction and back upon itself on the line of bend 18 bringing the construction to the form shown in Figs. 4, 90 5 and 6. This provides two halves or parts 24 of the body of the blank arranged in 95 back-to-back relation with the flanges 23 extending out at each side. The lower corners of these flanges at 25 are bent in from the planes of the bodies of the flanges. The dimensions of the parts are such that the width of the connector is substantially the internal width of the opening of the tube and the distance from edge to edge of oppositely extending flanges is substantially 100 the dimension across the tube in the opposite direction. The bend at the center causes the two connector parts or halves to spring away from each other and when these parts are brought into contact for insertion in the end of the tube the bent over corners 25 of the flanges permit the connec-

105

tors entering readily into the tubes and the yielding or expanding tendency of the connectors causes them to tightly engage opposite internal walls thereof to hold the connectors against inadvertent vertical movement after being positioned. That is to say, this expansive action prevents the connectors from dropping down into the tubes or being inadvertently pulled out of them. The upright extensions indicated in full lines at 26 in Fig. 2 and in dotted lines in Fig. 1 are easily positioned over the protruding ends of the connectors and additional assemblage may thus be erected upon the shelf, 15 rack or other lower construction.

It will be noted that the connectors are located wholly within the tubes and that a mere line of contact between the connected parts constitutes the sole evidence of their 20 connection. Since the connectors are constructed of sheet metal as described they may be cheaply provided and after once being positioned their expanding or yielding qualities prevent vibration or jarring from 25 loosening them or reducing the effective character of the connection.

It is thought that the invention and many of its attendant advantages will be understood from the foregoing description, and 30 it will be apparent that various changes may be made in the form, construction and arrangement of the parts without departing from the spirit and scope of the invention or sacrificing all of its material advantages, 35 the form hereinbefore described being merely a preferred embodiment thereof.

I claim:

1. The combination of shelf framing, including tubular uprights at the corners of 40 rectangular section and having open tops, and sheet metal members folded to provide outstanding flanges insertable therein and into firm frictional contact with said uprights for receiving the lower ends of similar uprights to permit upward extension of 45 said framework.

2. The combination of shelf framing, including tubular uprights at the corners of 50 rectangular section and having open tops, and extension connectors adapted to be po-

sitioned in said open tops of said tubular uprights, and comprising metal sheets bent at their longitudinal centers to provide legs separable under the yielding influence of 55 said bend, said connectors being held in place in the tops of said uprights by said yielding connection and being adapted for insertion into open ends of similar uprights to provide upward frame extension.

3. The combination of shelf framing, including tubular uprights at the corners of rectangular section and having open tops, and extension connectors adapted to be positioned in said open tops of said tubular uprights to permit upward shelf extension and each comprising a metal sheet flanged at its ends and bent at its center, the central bend serving to insure firm engagement of the connector halves with the walls of the tubular uprights and the flanges serving to stiffen said connector parts.

4. The combination of shelf framing, including tubular uprights at the corners of rectangular section and having open tops, and extension connectors adapted to be positioned in said open tops of said tubular uprights to permit upward shelf extension, and each comprising a metal sheet folded back upon itself at the center and having flanges 70 extending out from the lateral sides, said flanges fitting neatly within said tubular uprights with the upper portion including the bend protruding in position to receive a similar upright.

5. The combination of shelf framing, including tubular uprights at the corners of rectangular section and having open tops, and extension connectors adapted to be positioned in said open tops of said tubular uprights to permit upward shelf extension, and each comprising a metal sheet folded back upon itself at the center and having flanges 80 extending out from the lateral sides, said flanges fitting neatly within said tubular uprights, the lower ends of said flanges being bent to permit easy insertion of the connectors into snug engagement with the uprights.

WALTER N. VANCE.
